UNITED STATES PATENT OFFICE.

WILHELM VON OECHELHAEUSER AND HUGO JUNKERS, OF DESSAU,
GERMANY.

GAS-ENGINE.

SPECIFICATION forming part of Letters Patent No. 508,833, dated November 14, 1893.

Application filed November 5, 1892. Serial No. 451,102. (No model.)

To all whom it may concern:

Be it known that we, WILHELM VON OECHELHAEUSER and HUGO JUNKERS, subjects of the Emperor of Germany, residing at Dessau, Germany, have invented certain new and useful Improvements in and Relating to Gas-Engines; and we do hereby declare the following to be a full, clear, and exact description of the invention, such as will enable others skilled in

10 the art to which it appertains to make and use the same, reference being had to the accompanying drawings, and to letters or figures of reference marked thereon, which form a part of this specification.

15 Our invention relates to gas engines and consists in structural features and in combinations of co-operative parts as well as in a novel method of working such engines.

The dimensions of high power gas engines 20 as heretofore constructed are comparatively great, their construction expensive, and their operation unreliable by reason of premature explosions of the charge of combustible gas, while the consumption of gas with the increased power and size is not reduced to the extent it was thought it would be.

Our invention has for its object the provision of means whereby these disadvantages are remedied: first, in fully clearing out all 30 ducts of combustion from the working cylinder by fresh compressed air after the gases have done their work so that a cooling of the cylinder walls and a low temperature of the remaining air at the beginning of the compression stroke is secured and in consequence thereof a high compression of the charge mixed afterward with gas is obtainable without premature explosion; secondly, by this high degree of compression a high pressure 35 of combustion up to sixty atmospheres and even higher being attained so that the working cylinder may be of considerably reduced diameter; thirdly, in that the air and gas are separately introduced into the working cylinder by different pumps and the gas being introduced into the charge of air only after the latter has begun to be compressed so that any loss or waste of gas during the expulsion of combustion products is fully avoided; fourthly, by the high compression of the charge up to ten atmospheres and even higher and by

avoiding all lateral chambers or passages being in other gas engines open during combustion and expansion a comparatively great reduction in the surfaces to be cooled and in 55 consequence thereof a saving in consumption of gas is attained.

As in many gas engines now in use, we employ twin pistons having motion toward and from each other, but their working functions 60 are quite different from the older systems. Our pistons perform three functions, to wit:—As they approach each other they compress the charge of air. As they recede from each other they transmit the power exerted upon 65 them by the explosive charge to a driving shaft, and act as valves to control the inlet for the air as well as the exhaust for the products of combustion, whereby special valves and valve operating mechanisms are dispensed with. The pistons do not perform the function of suction pistons to draw air or gas 70 or both into the working cylinder. This introduction is effected by two pumps one of which compresses the air and the other the gas, the 75 compressed air being also used to drive out fully the products of combustion and cool the working cylinder after each explosion and at a time when the pistons have reached the 80 limit of their movement from each other, the pure air remaining in the working cylinder being then compressed by the pistons as they approach each other. When the pistons have approached each other a certain distance and the charge of air has begun to be compressed, 85 then gas is introduced into said air to form the explosive mixture. By admitting air and gas separately to the working cylinder, by the complete expulsion therefrom of the products of combustion and the high compression and 90 high pressure of the combustible gas together with a comparatively great reduction in the surfaces to be cooled the consumption of gas is much less than in other engines of like power. But that our invention may be fully 95 understood we will describe the same in detail, reference being had to the accompanying drawings, in which—

Figure 1 is a longitudinal sectional view taken on line *a*, *b*, of Fig. 3, of a gas engine 100 embodying our invention. Fig. 2 is a similar view thereof taken on line *c*—*d*, of said Fig.

3, which latter is a horizontal central sectional view, and Figs. 4 and 5 are cross-sectional views taken on or about on lines $e-f-g-h$, and $i-k-m$, respectively of Fig. 3.

5 In the above described figures of drawings, A, indicates the working cylinder; B, and C, the two pistons which are shown of the same diameter and having substantially the same throw, but it will be understood that although 10 this construction and motion of the pistons is preferred, they may be made of different diameters and have a different throw or amplitude of motion. The rod of piston, B, is connected to a crank, D, on the driving shaft 15 that carries a fly and belt wheel, W, and W', respectively at its opposite ends. The piston, C, carries at its outer end a cross-head, I, to opposite ends of which is connected one 20 end of two connecting rods, H, and F, respectively, the opposite end of said rods being connected to cranks, E, on said driving shaft, S.

The cylinder A, is jacketed as usual, and below the same is arranged an air reservoir, 25 R, from which the air is supplied to the cylinder through an annular channel or passage, R', and through peripheral ports, 1, formed in the working cylinder near its right hand end, said cylinder being provided with a corresponding set of exhaust ports, 2, near its 30 left hand end, which ports open into an annular channel or passage, R², in communication with the exhaust pipe, as shown in Figs. 1 and 4. The air inlet ports, 1, near one end 35 of the working cylinder are in line with the exhaust ports, 2, near the opposite end thereof, the object of this arrangement being to obtain a direct passage for the compressed air from one end of the combustion or work 40 chamber to the other, when the pistons are at the limit of their throw from each other, in order to effectually and thoroughly remove or drive out the products of combustion.

The air supplied to the working cylinder is 45 compressed by a pump, L, and the gas by a pump, G, which pumps, with a view to simplify the construction of the engine are arranged on opposite sides of the working cylinder, their pistons, L', and G', being secured 50 to the connecting rods, H, and F, respectively, as more clearly shown in Fig. 3. The air pump, L, is provided with a slide valve controlled in any usual or well-known manner by the driving shaft S. The gas is supplied 55 to pump, G, through pipe, P', a suitable check valve or back pressure valve, V², being interposed in said communication, the compressed gas being forced into the cylinder through a passage, A', the supply of gas being controlled by any suitable valve, as for instance, 60 a cylindrical valve, V', Fig. 5, whose operation is also controlled through well-known mechanism by the driving shaft, S.

In Fig. 3 we have shown the pistons in their 65 relative position at the moment of ignition of the charge, which ignition may be effected through the medium of the electric spark in

a well known manner, and as the construction and arrangement of electric ignitors are well known we have deemed it unnecessary 70 to illustrate the same in the drawings. The explosion of the charge of explosive gas drives the pistons away from each other, the pump pistons, L', G', moving with the working piston, C, drawing air and gas respectively into 75 their cylinders, the valves V, and V², Figs. 2 and 5, uncovering the inlet ports. As the pistons reach the limit of their motion from each other the piston B, uncovers the air inlet ports, 1, and the piston, C, the exhaust 80 ports, 2, a comparatively large volume of compressed air passing from reservoir, R, through cylinder, A, driving out the products of combustion. On the return movement of the pistons said ports close, the air drawn into pump 85 cylinder, L, being forced into reservoir, R, while the air in cylinder, A, is compressed and the gas admitted to pump, G, is held under pressure therein until the pistons, B, C, have reached a certain position toward each other. 90 The valve, V', Fig. 5, opens to admit gas into the now fully compressed charge of air under a pressure greater than that of the air itself, the valve V', closing immediately after such admission of gas, when the charge of combustible gas is again ignited and the operations 95 described repeated.

The connections between the pistons and driving shaft are such that the ignition of the charge takes place at or about the time when the cranks, D, and E, are on their dead points or centers, as shown in Fig. 3, the cranks, E, being slightly in the lead, so that both said cranks as well as crank, D, will be carried over their dead points by a minimum expenditure of power.

It will be seen that the pistons perform the function of valves for the air admission ports and the exhaust ports for the products of combustion which latter are effectually and completely expelled by the compressed air which is not only due to the relative arrangement of the air inlet and exhaust ports as hereinabove set forth, but to the absence of lateral chambers or passages leading into the combustion chamber usually found in twin piston gas engines, which chambers or passages are then uncovered during combustion and expulsion and retain combustion products which cause in those engines premature 115 explosions during compression of the charge. On the other hand the expulsion of the products of combustion is effected at a much smaller expenditure of power than is the case in gas engines provided with a separate air inlet valve, for the reason that the pistons, B, and C, control the inlet ports for the air and the exhaust ports for the products of combustion whereby special valve mechanisms are dispensed with, the said pistons uncovering simultaneously comparatively large inlet and exhaust areas, so that a complete 120 expulsion of the products of combustion takes place, whatever may be the speed of the pis- 125

tons and driving shaft, at a comparatively small overpressure of air and a small expenditure of power, the exhaust taking place when the cranks D, and E, are on or about on their dead centers.

5 After the products of combustion have been exhausted the combustion chamber or that portion of the cylinder, A, between the piston faces is completely filled with pure or 10 fresh air so that the temperature at the commencement of the compression is lowered as much as possible, whereby a premature ignition of the charge of combustible gas is prevented.

15 Having thus described our invention, what we claim as new therein, and desire to secure by Letters Patent, is—

1. A gas engine comprising a working cylinder having peripheral inlet and exhaust 20 ports near its opposite ends, respectively and reciprocally movable pistons adapted to control said ports, for the purpose set forth.

2. A gas engine comprising a working cylinder having peripheral inlet and exhaust 25 ports near its opposite ends, respectively, said ports in line with one another, and reciprocally movable pistons adapted when in a given relative position to uncover said ports simultaneously, for the purpose set forth.

30 3. A gas engine comprising a working cylinder having air and gas inlet ports, exhaust ports for the products of combustion, two pistons reciprocally movable in said cylinder and controlling said air inlet ports and the exhaust ports, an air compressing pump connected with the air inlet ports, a gas compressing pump connected with the gas inlet port, and a valve adapted to control the admission of the gas to said gas inlet port, for 40 the purpose set forth.

4. A gas engine comprising a motor shaft, a working cylinder provided with peripheral air inlet and with like exhaust ports near its opposite ends, two pistons connected with the motor shaft and reciprocally movable in said cylinder, said pistons controlling the aforesaid inlet and exhaust ports, and a compressed air reservoir connected with said inlet ports, in combination with air and gas compressing pumps the pistons thereof secured to the rods connecting one of the cylinder pistons with the motor shaft, said air compressing pump having its exhaust connected with the air reservoir, and said gas compressing pump having its exhaust connected with the working cylinder for the purpose set forth. 45 50 55

5. In a gas engine, the combination with the working cylinder provided with separate air and gas inlet ports and with exhaust ports, two pistons reciprocally movable in said cylinder and controlling the air inlet and the exhaust ports, of an air compressing pump connected with the air inlet ports of the cylinder, a gas compressing pump connected with the gas inlet port of said cylinder, and a valve 60 controlled from a movable element of the engine and controlling the supply of gas to the cylinder, said pistons and valve controlling devices operating to admit air under pressure into the cylinder while the exhaust ports are 65 open, close both air inlet and exhaust ports simultaneously compress the air in the cylinder and then admit a charge of gas into the compressed charge of air, for the purpose set forth. 70
